Primary Examiner — Joseph Kukella(74) *Attorney, Agent, or Firm* — Fredrikson & Byron, P.A.(57) **CLAIM**

An ornamental design for an enclosure for a security system control unit, as shown and described.

DESCRIPTION

FIG. 1 is a perspective view of the enclosure for a security system control unit.

FIG. 2 is a front elevation view thereof.

FIG. 3 is a right side elevation view thereof.

FIG. 4 is a left side elevation view thereof.

FIG. 5 is a top plan view thereof; and,

FIG. 6 is a bottom plan view thereof.

The rear elevation view of the enclosure for a security system control unit is hereby disclaimed and forms no part of the claimed design.

The broken lines in the drawings depict portions of the enclosure for a security system control unit in which the design is embodied that form no part of the claimed design.
